TIME-PIECE

Ernest E. Spranger, New York, N. Y.

Application May 14, 1932. Serial No. 611,269

4 Claims. (Cl. 58—126)

The present invention relates to time-pieces. The necessity of changing the hour hand setting of the time-piece to adapt the latter to local time, i. e. from daylight saving time to standard time or vice versa or during travel, is injurious to the time-piece mechanism and in addition destroys the accuracy of the time reading which usually requires long and patient setting and resetting to acquire. This is especially true of electrically operated time-pieces and expensive finely regulated mechanical time-pieces.

An object of the present invention is to provide means for changing the hour hand setting without interfering in any way with the time-piece mechanism.

Another object of the invention is to provide such means whereby the hour hand setting may be changed without destroying the accuracy of the time reading.

Still another object is to provide a device which may be applied to existing time pieces without modifying the structure in any way.

Still another object is to provide a device which is simple and inexpensive to manufacture.

With the above and other objects in view as will be apparent, my invention comprises the novel combination, construction and arrangement of elements to be hereinafter more fully described, shown and defined in the appended claims.

In the accompanying drawing, which is to be read in conjunction with this specification, and in which similar reference characters denote corresponding parts:

Fig. 1 is illustrative of the application of my invention to a time-piece such as an electric clock or the like;

Fig. 2 is an enlarged sectional detail of one form of my device;

Fig. 3 is a section along line 3—3 of Fig. 2 seen in the direction of the arrows;

Fig. 3a is a section along line 3a—3a of Fig. 3 seen in the direction of the arrows; and

Fig. 4 is a view similar to Fig. 3 of a modified form of my device.

Referring to the drawing, 10 denotes the hour hand shaft of a time-piece and 11 denotes the usual minute hand shaft. 12 denotes a sleeve 50 which is adapted to be mounted on the hour hand shaft 10 and be frictionally or otherwise suitably retained thereon. On the circumferential outer wall of said sleeve there are provided a plurality of equi-spaced notches or recesses 13 preferably twelve in number spaced 30

degrees apart about the circumference. Rotatably mounted on said sleeve is the hour hand 14 of any type or shape. Extending from said hour hand is a resilient member 15 of metal or other suitable material which may engage in any one of the aforementioned recesses 13 and when so engaged prevents rotation of said hour hand on said sleeve 12 and retains it in a determined position. Thus with said member engaging any one of said recesses the hour hand of the time-piece is moved by shaft 10 in the usual relationship with respect to the minute hand 16 on shaft 11 and indicates time in the usual manner. If for example these hands indicate standard time and it is desired to change to daylight saving time, the hour hand is rotated by hand until the resilient member 15 engages in the next notch in the clockwise direction, which being 30 degrees apart from the first named shaft results in a time reading exactly one hour later than that previously read. This rotation is effected without in any way adjusting the minute hand or the clock mechanism. Vice versa to reset from daylight saving to standard time, the hour hand is rotated in counter-clockwise direction. In view of the plurality of 30 degree settings the hour hand may be advanced or set backward any given number of hours to meet the conditions in different localities for example for transcontinental or transoceanic travel.

The sleeve 12 may have an annular shoulder 17 which prevents removal of the hand 14 therefrom. The resilient member 15 may be integrally formed with the hand 14 if desired or otherwise suitably attached thereto. In the modification shown the said member is integrally formed with the latter and bent around under said hand in the manner shown so that its free end 15' may engage any recess 13. The relative position of the hands on their shafts with respect to the dial face D is clearly shown in Figs. 1 and 2. Naturally, the transparent front cover C of the time-piece must be readily removable for manipulation of the hour hand.

A different modification of my device may be constructed as follows:

The wall of a sleeve 12', similar to sleeve 12 except for the recesses which are not needed, may be cut away partially as at 12' at that portion on which the hour hand is mounted and provided there with a projection 18. The hour hand 19 of any usual construction having a sleeve 19' is adapted to be rotatably mounted on said sleeve 12'. The sleeve 19' of the hour

hand has a resilient member as a spring 20 mounted therein as to extend as a chord across a portion of the opening in said sleeve 19'. Said member has provided therein two or more 5 equi-spaced notches 20' so spaced apart that a rotation of 30 degrees by the hour hand may be made between notches. The sleeve 19' is mounted on the sleeve 12' with the projection 18 engaging one of said notches. The portion 10 of the spring 20 between notches projects into the path of said projection to prevent rotation of said hand on sleeve 12' without first overcoming the action of said spring. There is further sufficient pressure provided by the reaction 15 between said spring and projection 18 to frictionally retain sleeve 19' of hand 19 on sleeve 12. If a shift of the hour hand is necessary to accommodate a different time standard, e. g. standard time to daylight saving time the 20 hour hand is rotated in clockwise direction until the projection 16 engages the next succeeding notch in said spring. The time-piece will now indicate daylight saving time, or vice versa when changing from daylight saving time to 25 standard time is required. During the hour hand shift of 30 degrees or more in either direction neither the shaft on which it is mounted nor the mechanism of the time piece is disturbed in any way.

30 In either modification, if desired, the sleeve can be eliminated. The surface of the hour hand shaft in such event at the portion where the hour hand is mounted will have to be shaped to conform to the respective shapes of 35 the respective sleeve surfaces and, of course, the hour hand will then be rotatably borne directly on the respective hour hand shaft.

The 30 degree spacing mentioned in both 40 modifications between recesses or notches may, of course, be varied to suit and is not to be construed as a limitation of applicant's invention.

It is easily seen that there are many variations of my device which may be made without 45 departing from the spirit of my invention and I, therefore, do not wish to be limited to the details shown and described.

What I claim is:—

1. In combination with the hour hand shaft of a time piece, a sleeve mounted on and retained thereon, said sleeve having a plurality of regularly disposed recesses about its circumferential wall, a hand rotatably borne on said sleeve and means extending from said hand to engage in any of said recesses whereby said hand may be rotated a determined amount at a time independently of any movement of said hour hand shaft. 80
2. In combination with the hour hand shaft of a time piece, a sleeve mounted on said shaft and retained thereon, said sleeve having a plurality of regularly spaced recesses about its circumference, a hand rotatably borne on said sleeve, a resilient member extending from said hand and adapted to engage in any one of said recesses whereby said hand may be rotated a determined amount at a time independently of any movement of the hour hand shaft. 90
3. In combination with the hour hand shaft of a time piece, a sleeve mounted on said shaft, frictionally retained thereon and rotatable therewith, said sleeve having a plurality of regularly spaced recesses about its circumference, a hand rotatably borne on said sleeve, a resilient member extending from said hand and adapted to engage in any one of said recesses whereby said hand may be rotated a determined amount at a time independently of any movement of the hour hand shaft. 100
4. In combination with the hour hand shaft of a time piece, a sleeve mountable on and frictionally retained thereon, a hand rotatably mounted on said sleeve, the latter being cut away in part at the point of mounting of said hand and having a projection and a spring member having regularly disposed notches mounted on said arm, said projection adapted to engage any of the said notches whereby said hand may be rotated a predetermined amount at a time independently of any movement of said hour hand shaft. 110
5. In combination with the hour hand shaft of a time piece, a sleeve mounted on and retained thereon, a hand rotatably borne on said sleeve, the latter being cut away in part at the point of mounting of said hand and having a projection and a spring member having regularly disposed notches mounted on said arm, said projection adapted to engage any of the said notches whereby said hand may be rotated a predetermined amount at a time independently of any movement of the hour hand shaft. 115
